UNITED STATES PATENT OFFICE.

GEORGE H. MEGQUIER, OF ANACORTES, WASHINGTON.

METHOD OF PACKING SHINGLES AND MACHINE THEREFOR.

SPECIFICATION forming part of Letters Patent No. 495,424, dated April 11, 1893.

Application filed February 15, 1893. Serial No. 462,476. (No model.)

To all whom it may concern:

Be it known that I, GEORGE H. MEGQUIER, a citizen of the United States, residing at Anacortes, in the county of Skagit and State of Washington, have invented certain new and useful Improvements in Methods of Packing Shingles and in Machines for the Same; and I do hereby declare the following to be a full, clear, and exact description of the invention, such as will enable others skilled in the art to which it appertains to make and use the same.

My invention consists of a novel method of packing shingles and a machine for packing them in this form. The shingles packed by my method form a bunch which is much longer than the usual bunch and in which there is a series of layers of shingles having their butts all one way, thus making the bunch in cross section a truncated pyramid and as broad as a shingle is long.

The machine consists of a box in which to lay the shingles, a set of guide strips upon which the shingles are laid at one end and slid to the other, and the mechanism by which these strips are raised when the layer is completed and then falls back in readiness for the next layer.

There are other details of mechanism, all of which will be fully described.

In the drawings, Figure 1 is a front elevation of my machine with some of the front removed to more clearly show the remainder. Fig. 2 is an end elevation with the end pieces removed for a similar purpose. Fig. 3 is a detail of the mechanism for releasing the wheel C, and for automatically counting the layers of shingles and giving an alarm when the right number is in place. Fig. 4 is a side view of one of the compressing fingers. Fig. 5 is an end elevation of a bunch of shingles packed in this manner, and Fig. 6 a perspective of the same. Fig. 7 is a detail showing a cross section of the guides D.

Mounted upon a suitable frame work and at such a height as will be most convenient, is a box, shaped as the bunch of shingles is to be when packed. The sides of this box A, and A², slope away from and toward the operator thus having one corner down. The end piece A' is placed only at one end of the box. It is here shown as at the left end which is

where it would be for a right handed operator but might be placed so that the machine could be operated from the other end for a left handed man or if any other circumstance required it. This box is not a fixed part of the machine but rests in a similar shaped cradle O, O, built in the machine. The object of this is that the man who packs the shingles may not have to stop to bind them but that the box A, and the bunch of shingles contained therein may be taken off of the machine and replaced by an empty box while another man does the binding. I have shown in dotted lines, Fig. 1, the end O, of the cradle as being hinged at its lower edge so that the box A. may be slid out at that end instead of having to lift it out. This hinged end would be fastened by a hook and catch as shown or any other convenient means. Instead of making the box with three sides, or rather two sides, and an end as shown, it may be made with only two sides, being in fact a sort of trough in which the shingles are to be placed. Fastened to the frame above and back of this box are two guides, D, which are in cross section as shown in Fig. 7, and are pivoted near their middle at D'. Sliding within these guides is the frame composed of the end pieces B, B, bars B', B', and braces B². This is composed of thin wooden slats in order that it may be light. The bars B', B', may have their upper surfaces covered with thin sheet metal in order to make a better sliding and wearing surface for the shingles to slide upon. Attached to the lower bar B', at its center is a small leather strap or cord B³. This passes up and around a pulley C', and then down and around the pulley C, to which the end is fixed. This pulley is attached to the shaft C⁵, in such a manner that it may be released therefrom and turn freely thereon. Attached to the shaft C⁵, is the small pulley C², which carries a strap which is also attached to one end of a lever C³, the other end of the lever resting upon the floor. When the lever C³, is pressed down by the foot it will rotate the shaft C⁵, and winding up the strap B³, will raise the slats B', out of the box A. The wheel C, is loose upon the shaft C⁵, but carries on its side a dog F. Alongside of this pulley and fixed to the shaft is the disk or pulley C⁴, having a notch in its periphery which engages the dog F, and thus rotates the

pulley C. A spring F², presses the dog toward the periphery of the disk C⁴. F' is a stop which is attached to the frame of the machine and projects into the path of travel of the inner end of the dog. Now when the shaft and its disk C⁴, are rotated in the direction of the arrow in Fig. 3, the pulley C, is carried along and the belt wound up. When it has made nearly a full revolution the inner end of the dog strikes the stop F', and is thereby raised out of the notch in the disk C⁴, and the pulley immediately turns backward, being impelled thereto by the weight of the sliding frame. The stop F', also acts as a positive stop to its rotation in this direction. The shaft C⁵, is rotated backward and the lever raised by the coiled spiral spring C⁶, which is attached at one end to the pulley C², and at the other end to a block C⁷, which forms a bearing for the shaft.

At the upper edge of the packing box at A³, the bottom is dropped to permit of the insertion of one of the straps for binding the bunch together. If the shingles are not to be bound upon the machine, this will not be necessary.

Passing along the rear side of the machine is the shaft E. This shaft has three eccentrics upon it, one near each end and one near the middle. Upon these eccentrics are the hooked compressing fingers E². When not in use these compressing fingers are thrown up vertical. When a bunch is to be compressed they are brought down upon the tips of the shingles and the binding strip with which they engage. The shaft E, has a lever or crank arm E³, attached and this is connected to the foot lever E⁵, by the rod E⁴. When the compressing fingers E², are in place the bundle is compressed by stepping upon the lever E⁵, and it is then nailed. If the bunch is not to be bound on the machine this mechanism may of course be omitted. In this case as soon as the bunch has been packed the end O', is dropped and the filled box is pushed out upon a slide way of some sort.

In order that it may not be necessary to waste time in counting the layers of shingles, I have put on an automatic counter and alarm which will ring a bell at the commencement of the last layer. The operator will be thereby warned that the bunch is about completed and will proceed to remove it or bind it as soon as that layer is completed and without wasting any time. This mechanism is shown in Fig. 3. Adjacent to the wheel C, is pivoted a ratchet wheel I, which has as many teeth as there are to be layers of shingles in the bunch, or as I have made it, twenty-one notches. The same center carries the pawl lever H. This lever besides carrying the pawl H², carries another lever H', which in reality, forms with the lever H, a compound hinged lever. A stop H⁵, prevents them from yielding in one direction, and a spring H³, both holds the pawl H², in engagement with the ratchet wheel and the stop H⁵, against the side of the lever H'. A stop H⁶, prevents the

levers from moving more than a certain distance in one direction while a spring H⁴, holds them against the stop. The outer end of the lever H', projects into the path of the pin F³, or some convenient projection on the wheel C. When the wheel C, revolves in the direction of the arrow it will bend the arm H, but will not operate the pawl. On its return movement, however, it will engage the lever and move it forward until it has passed out of the arc of its movement. This will advance the ratchet wheel one notch. Upon the ratchet wheel is a pin or projection I², so placed as to engage the end of a lever I', which carries a spring hammer. Once in each revolution this will engage and throw back this lever which upon being released will strike the bell I⁴, thus giving the alarm.

The wheel I, may be connected to a further counting mechanism which will register the number of bunches packed and thus keep a record of the number of shingles packed on any machine.

The operation of the machine is as follows: An empty packing box is inserted in its place on the cradle, the sliding frame B, B', is let down until its lower bar rests in the angle at the bottom as shown in Fig. 2. The machine is supposed to stand where the right hand end is convenient to the supply of shingles. The shingles are placed, butts down, upon the bars B', at the right hand or nearest end. This is the open end of the box and where the operator will stand. As the shingle is placed upon the bars B', by the left hand, it is at the same time slid to the left or farther end of the box while with the right hand the operator picks up the next shingle which is transferred to the left hand and by it placed as was the first. In this way the shingles are placed until the layer fills the box when the lever C³, is depressed by the foot which by the mechanism described raises the sliding frame out of the box. As the layer of shingles which has been placed upon the bars B', is resting at an angle it will not be disturbed thereby, the bars B', being simply pulled from under them, allowing them to drop to the bottom of the box. The releasing mechanism shown in Fig. 3, allows the bars B' to drop immediately they have reached their uppermost position. As they come down they strike on top of the layer of shingles which are in the box and slide upon them to the bottom of the box. Another layer of shingles is placed upon the bars in the same manner and then allowed to drop upon the preceding layer by withdrawing the bars as before described. This process is kept up until sufficient layers of shingles to make the required amount have been placed in the box when the shingles are bound on the machine or the box removed for binding, and replaced by an empty box. The guides D, being pivoted and having their pivots placed above the point of intersection of the two sides of the completed bunch, the bars will always strike

on top of the shingles. The pivoting of the guides allows them to change their direction to correspond to the constant change of angle of the layers of shingles as the bunch is built up. Attached to the frame is the stop A which prevents their lower ends from dropping too far. The bunch of shingles packed in this manner will have the appearance shown in Figs. 5 and 6. If the shingles are not to be bound on the machine the filled box is removed and an empty one put in its place. If they are to be bound on the machine one of the binding strips 3, with its three bands 4, 4, and 5 attached, see Fig. 6, is placed in the recess A³, before commencing packing. When the packing has been completed the sliding frame is raised in its guides and then tilted to the position shown in dotted lines in Fig. 2. The second binding strip 3, is then placed on top of the shingles at their tips and the compressing fingers E², E², brought forward upon it and the tips of the shingles compressed thereby and the two binding strips fastened by nailing the bands upon the second. For this purpose it is advisable to use a long nail which will go clear through the bunch of shingles and into the strip upon the other side. As this will only go through the extreme tips of the shingles it will not in the least injure them and will make it impossible for the strips to come off the bunch. These binding strips are quite light and have a metal strip at each end of the bunch and a third in the middle which passes over the tips of the shingles as plainly shown in Fig. 6. The other set of binding strips 2, 2, are not put on as yet. The reason for this is as follows: The binding strips 3, 3, at the tips of the shingles are sufficient to hold the shingles securely for any ordinary handling. As the bunch has been compressed at the tips, it results in making the butts of the shingles looser than before. Each layer of shingles will be slightly separated from the next. In this loose condition of the butts the shingles are stacked up in the dry house. In consequence of this the air can penetrate to the very center of the bunch and the shingles will dry out much quicker than they otherwise would. This increases the capacity of the dry house and also more thoroughly dries the shingles making them weigh less and making the freight rates per thousand lower. When the shingles are placed in the dry house, the lower binding strips which have previously been fastened together by bands of the exact length necessary, are dropped loosely over the bunch. After they have been dried and before removing them from the dry house these lower or butt strips are driven down by a hammer thus tightening them just as a cooper tightens a hoop on a cask. The central band 7, is afterward nailed on just as was the band 5, except that short nails are used. The bunch is thus securely bound so that there is no possibility of its getting loose or falling to pieces, a thing of common occurrence with shingles put up in the ordinary

manner. The strap 5 may not be put on until after the bunch has been dried and the upper strip been similarly tightened. Indeed it 70 may be omitted entirely and two or three long nails which will go entirely through and clinch on the other side be used instead.

In preparing the binding strips for the butts of the shingles the bands may be made of such 75 a length that the strips will go to the edge of the bunch or short enough so that they will stop short of the edge. If the latter they should stop a distance from the edge not less than the width of the tip strips. By so placing the butt strips, when the bunches are piled upon each other the tip strips of one bunch will occupy the space outside of the butt strips of the bunch above and below, instead of lying on top of the butt strips as 85 would be the case were the butt strips at the edge of the bunch unless the bunch were moved a little to one side.

The shingles packed by this method will pack together with less waste space than is 90 possible with the old style, are more convenient to handle and less liable to get loose. They can be dried lighter in the same time and can be packed faster. An active man who will pack thirty thousand by the old 95 method can pack sixty thousand with my machine. There are less joints to make, being twenty-one by my method and fifty by the old. It is not necessary for him to watch constantly where he is laying the shingles. He 100 places them all in one place and then slides them along which makes it possible for him to give his attention to the other parts of the work, all of which makes the work more rapid. A bunch of shingles put up in this 105 form is much more convenient to handle, it being possible to pick it up with one hand by grasping it by the two tip strips at their middle. They are also much more convenient for the carpenter when he is laying them as the 110 butts are all one way and he has them all close at hand.

Most shingles are sixteen inches long, but some are eighteen. To accommodate my machine to both sizes, the recess A³, in the removable box is made low enough down for the shorter length when the shingles are to be removed for binding. When they are to be bound before removing, the recess is made the proper distance from the opposite edge 115 of the box for the longer size and then when packing the shorter size a two inch plank is put on the bottom side of the box so that the shingles will not drop as far and the tips be even with the top edge of the box. 120 125

When the shingles are bound upon the machine the removable box is not necessary. In either case the end piece O should be hinged as shown at O', so that the box or the shingle bunch may be slid out without lifting. In 130 using the removable box it is well to not have the two side pieces of the cradle or box supports come together at the bottom angle but to be slightly separated so that any dirt get-

ting in will fall through. This construction is shown in Fig. 2.

To raise the lever E⁵, and crank arm E³, a spiral spring similar to C⁶, may be used.

5 Having thus described my invention, what I claim, and desire to secure by Letters Patent, is—

1. In a machine for packing shingles, the combination with a box or form similar in 10 size and shape to a bunch of shingles, of guide or supporting bars and means by which they may be withdrawn, allowing the shingles to drop into place and then returned in position for receiving the next layer of shingles, 15 substantially as shown and described.

2. In a machine for packing shingles, the combination with a box or form similar in 20 size and shape to a bunch of shingles, of supporting strips for receiving a layer of shingles, means for withdrawing these strips and allowing the shingles to drop into place, and 25 means for disengaging these strips from the withdrawing mechanism as soon as they are clear of the shingles, thus permitting them to return to their place at once, substantially as shown and described.

3. In a machine for packing shingles, the combination with a removable box having 30 two sides and an end and similar in shape to a bunch of shingles, a cradle for the same, of supporting fingers for receiving the shingles and means for withdrawing them from under the shingles and returning them on top of the same, substantially as shown and described.

35 4. In a machine for packing shingles, the combination with the removable box, a cradle or form for holding it having the hinged end piece O', of guide and supporting bars B', for receiving the shingles, and means for withdrawing the same from under the shingles and immediately returning them in place 40 for receiving the next layer, substantially as shown and described.

5. In a machine for packing shingles, the 45 combination with the box or form for holding the shingles, of the sliding frame B, B', guides D, and means for moving the frame up in the guides and then letting it drop again, substantially as shown and described.

50 6. In a machine for packing shingles, the combination with the box or form for holding the shingles and the sliding frame, of the guides D, pivoted near their center and mechanism whereby the sliding frame is raised in 55 the guides D, and then dropped upon the

shingles, substantially as shown and described.

7. In a machine for packing shingles, the combination with the box or form for holding the shingles the sliding frame B, B', and 60 guides D, of the strap B³, attached to the sliding frame, guide pulley C', pulley C, to which the strap is attached and means for rotating said pulley C, and thus lifting the sliding frame, substantially as shown and described. 65

8. In a machine for packing shingles, the combination with the box or form for holding the shingles, the sliding frame B, B', guides D, and strap B³, attached thereto, of the guide pulley C', pulley C, to which the strap is also 70 attached and means for rotating said pulley C, and means for releasing it from the rotating mechanism when the frame has reached the proper height, substantially as shown and described. 75

9. In a machine for packing shingles, the combination with the box or form for holding the shingles, supporting fingers for receiving the shingles, and means for withdrawing them from under the same and then returning them 80 to the top of the bunch, of automatic mechanism operated thereby which will sound an alarm at the beginning of the last layer, substantially as shown and described.

10. In a machine for packing shingles, the 85 combination with the box or form for holding the shingles, supporting bars therein for receiving the same, and means for withdrawing these bars and returning them to their place, of a compressing device which will compress 90 one edge of the bunch for binding, substantially as shown and described.

11. The method of packing shingles which consists in first placing a layer of shingles with their butts all one way, superimposing 95 upon this another layer having the butts in the same direction and so continuing until the bunch contains the desired number of shingles, then placing binding strips on opposite sides at the tips and securing them 100 by bands, then drying the shingles while the butts are loose and then securing the butts by similar binding strips, substantially as shown and described.

In testimony whereof I affix my signature in 105 presence of two witnesses.
